US0D1107007S

(12) **United States Design Patent** (10) **Patent No.:** **US D1,107,007 S**
(45) **Date of Patent:** **** Dec. 23, 2025**

(54) **STAND FOR AN AUDIO DEVICE**

(71) Applicant: **SONOS, INC.**, Goleta, CA (US)

(72) Inventors: **Vincent Wang**, Santa Barbara, CA (US); **Edward Mitchell**, Santa Barbara, CA (US); **Eduardo Salazar**, Oxnard, CA (US)

(73) Assignee: **SONOS, INC.**, Goleta, CA (US)

(**) Term: **15 Years**

(21) Appl. No.: **30/007,844**

(22) Filed: **Jun. 11, 2025**

Related U.S. Application Data

(63) Continuation of application No. 29/988,569, filed on Feb. 4, 2025, now Pat. No. Des. 1,082,756, which is a continuation of application No. 29/959,931, filed on Aug. 28, 2024, now Pat. No. Des. 1,066,303, which is a continuation of application No. 29/868,436, filed on Dec. 2, 2022, now Pat. No. Des. 1,045,836.

(57)

CLAIM

The ornamental design for a stand for an audio device as shown and described.

DESCRIPTION

FIG. 1 is a front elevation view of a stand for an audio device, showing the new design.

FIG. 2 is rear elevation view thereof.

FIG. 3 is a top plan view thereof.

FIG. 4 is a bottom plan view thereof.

FIG. 5 is a right side view thereof.

FIG. 6 is a left side view thereof.

FIG. 7 is a first perspective view thereof; and,

FIG. 8 is a second perspective view thereof.

The features shown in broken lines form no part of the claimed design.

1 Claim, 7 Drawing Sheets
